UNITED STATES PATENT OFFICE.

FREDERICK W. OLSEN, OF MOUNT PLEASANT, WISCONSIN.

DESIGN FOR A JARDINIÈRE-STAND.

SPECIFICATION forming part of Design No. 36,086, dated September 30, 1902.

Application filed August 18, 1902. Serial No. 120,162. Term of patent 7 years.

To all whom it may concern:

Be it known that I, FREDERICK W. OLSEN, a citizen of the United States, residing at Mount Pleasant, in the county of Racine and State 5 of Wisconsin, have invented and produced a new, original, and ornamental Design for Jardinière-Stands; and I do hereby declare the following to be a full, clear, and exact description of the same, reference being had to 10 the accompanying drawings, forming a part thereof.

Figure 1 of the drawings represents a side elevation, and Fig. 2 a plan view, of a jardinière-stand embodying my new ornamental 15 design.

As shown in the drawings, the leading or material feature of my ornamental design consists of the unitary design made the sub-

ject of illustration, comprising a series of scrollwork-standards disposed or arranged 20 equidistant radial to horizontal intercepting rings B, that occur at different elevations, minor features of the design being the scroll ends b c, outer scrolls d e f, and inner scrolls g of each standard. 25

Having now described my invention, what I claim as new, and desire to secure by Letters Patent, is—

The ornamental design for a jardinière-stand, as herein shown and described. 30

In testimony whereof I affix my signature in presence of two witnesses.

FREDERICK W. OLSEN.
